UNITED STATES PATENT OFFICE.

LEWIS C. BAYLES, OF EASTON, PENNSYLVANIA, ASSIGNOR TO INGERSOLL-RAND COMPANY, OF NEW YORK, N. Y., A CORPORATION OF NEW JERSEY.

PERCUSSIVE TOOL.

1,080,880.

Specification of Letters Patent.

Patented Dec. 9, 1913.

Application filed February 3, 1912. Serial No. 675,286.

To all whom it may concern:

Be it known that I, LEWIS C. BAYLES, a citizen of the United States, and resident of Easton, in the county of Northampton and State of Pennsylvania, have invented a new and useful Improvement in Percussive Tools, of which the following is a specification.

The objects of this invention are to provide a novel rotation device for a tool steel, and a novel arrangement for feeding the motive fluid to the steel.

In the accompanying drawings, Figure 1 shows in longitudinal central section a percussive tool of the piston hammer type with my improved rotation device and motive fluid feeding device for the tool steel applied thereto, and Fig. 2 is a detail cross section through the rotation device.

The work piston is denoted by 1 and the chamber in which it reciprocates is denoted by 2. The rotation piston is denoted by 3 and the chamber within which it reciprocates is denoted by 4. The tool cylinder 5 is provided with a handle 6 and a front head 7. The valve chest seat 8 on the cylinder 5, has the usual motive fluid passages 9 and 10 leading to the opposite ends of the work piston chamber 2 and the usual exhaust passage 11. The main controlling valve, not shown, may be of any well known or approved construction. A bushing 12 is located within the cylinder 5, at the front end of the work piston chamber 2, which bushing may be keyed as at 13, to the cylinder to prevent the bushing from turning therein. The anvil block 14 is fitted to turn and have a limited sliding movement within the bushing 12. This anvil block has a motive fluid passage 15 therein, leading from its side to its front end. This passage 15 is always in communication with an annular chamber 16, which chamber is shown in the present instance as being located in

the inner wall of the bushing 12. This chamber 16 has a port 17 which is in open communication with a motive fluid passage 18 leading to the valve chest seat 8, which passage is independent of the passages leading from the valve seat to the work piston chamber 2. A chuck 19 is rotatably mounted in the front head 7 of the tool, which chuck is adapted to receive the shank of the hollow drill steel 20, the bore of which steel 55 is at all times in open communication with

the passage 15, in the anvil block 14. This chuck 19 is provided with a spur gear 21 which meshes with a pinion 22 in axial alignment with the longitudinally reciprocating rotation piston 3. This rotation piston 3 has a sliding interlocked engagement with the pinion 22, in the present instance, by providing the piston with a front extension 23, angular in cross section, fitted to reciprocate in the bore 24 of the pinion 22, its bore being of the same cross sectional shape as the extension 23. The movement of this rotation piston is under the same control as the work piston 1, by bringing the front and back ends of the rotation piston chamber 4 into open communication with the front and back ends of the work piston chamber 2, through ports 25, 26. A step by step rotary movement in one direction is imparted to the rotation piston 3, by means of a rifle bar 27, with which the piston has an interlocked sliding engagement, said rifle bar being arranged to be clutched to and released from the cylinder by a ratchet device 28 of any well known or approved construction.

By locating the rotation piston along the side of the work piston, the length of the tool is materially decreased and the tool is made more compact. It will also be seen that by providing an independent motive supply passage for the supply of motive fluid to the hollow drill steel through the anvil block, the operation of the work piston is not affected by said supply and a very simple and efficient arrangement is provided.

While I have shown this invention as applied to a percussive tool of the piston hammer type, it is to be understood that I do not wish to limit myself to such particular type of tool, but contemplate the use of my invention wherever applicable in percussive tools.

What I claim is:

1. In a percussive tool, a work piston, a rotation piston arranged along the side of the same and parallel therewith, their chambers and a chuck rotated from the rotation piston.

2. In a percussive tool, a work piston, a rotation piston, their chambers, a chuck, and a pinion geared thereto, said pinion being in axial alignment with and rotated by the rotation piston.

3. In a percussive tool, a work piston, a

rotation piston arranged along the side of the same and parallel therewith, their chambers, a chuck and a pinion geared thereto, said pinion being in axial alinement with and rotated by the rotation piston.

4. In a percussive tool, a work piston and a rotation piston arranged along the side of the same and parallel therewith, both being under the same motive fluid control and a chuck rotated by the rotation piston.

5. In a percussive tool, a work piston and a rotation piston both being under the same motive fluid control, their chambers, a chuck and a pinion geared thereto, said pinion being in axial alinement with and rotated by the rotation piston.

6. In a percussive tool, a work piston and a rotation piston arranged along the side of the same and parallel therewith, both pistons being under the same motive fluid control, their chambers, a chuck and a pinion geared thereto, said pinion being in axial alinement with and rotated by the rotation piston.

7. In a percussive tool, a cylinder, a work piston, a chuck, a pinion geared thereto, a rifle bar arranged to be clutched to and released from the cylinder and a rotation piston having a sliding interlocked engagement with said rifle bar and pinion for imparting a rotary movement to the chuck.

8. In a percussive tool, a cylinder, a work piston, a chuck, a pinion geared thereto, a rifle bar arranged to be clutched to and released from the cylinder, and a rotation piston having a sliding interlocked engagement with said rifle bar and pinion for imparting a rotary movement to the chuck, said work piston and rotation piston being under the same motive fluid control.

9. In a percussive tool, a cylinder, a work piston, a chuck, a pinion geared thereto, a rifle bar arranged to be clutched to and released from the cylinder and a rotation

piston having a sliding interlocked engagement with the rifle bar and provided with an extension having a sliding interlocked engagement with said pinion for imparting a rotary movement to the chuck.

10. In a percussive tool, a cylinder, a work piston, a chuck, a pinion geared thereto, a rifle bar arranged to be clutched to and released from the cylinder and a rotation piston having a sliding interlocked engagement with the rifle bar and provided with an extension having a sliding interlocked engagement with said pinion for imparting a rotary movement to the chuck, said work piston and rotation piston being under the same motive fluid control.

11. In a percussive tool, a work piston, its chamber, motive fluid inlet and exhaust ports therefor, a rotation piston arranged along the side of the work piston, its chamber and ports leading from the adjacent ends of the work piston chamber to the adjacent ends of the rotation piston chamber, whereby the rotation piston is under the same control as the work piston, and a chuck rotated from said rotation piston.

12. In a percussive tool, a work piston, a chuck, a rotation piston arranged along the side of said work piston and means including a rifle bar engaged by said rotation piston for rotating said chuck.

13. In a percussive tool, a work piston, a chuck, a rotation piston arranged along the side of said work piston and means including a rifle bar for rotating said chuck from said rotation piston.

In testimony that I claim the foregoing as my invention, I have signed my name in presence of two witnesses, this first day of February 1912.

LEWIS C. BAYLES.
